UNITED STATES PATENT OFFICE.

JAMES W. CASE, OF YPSILANTI, MICHIGAN, ASSIGNOR OF ONE-HALF TO
ALMERON CRANDALL, OF SAME PLACE.

MATTRESS.

SPECIFICATION forming part of Letters Patent No. 645,383, dated March 18, 1900.

Application filed December 1, 1899. Serial No. 738,907. (No model.)

To all whom it may concern:

Be it known that I, JAMES W. CASE, a citizen of the United States, residing at Ypsilanti, in the county of Washtenaw and State of 5 Michigan, have invented a new and useful Mattress, of which the following is a specification.

This invention relates to mattresses; and it has for one object to provide a new and useful article of this character so constructed as to permit of its being compactly rolled or folded when not in use, so as to occupy a comparatively-small compass, thereby facilitating the handling thereof for shipment or storage purposes.

A further object of the invention is to construct the mattress in a novel manner, whereby the same will readily adjust itself to the weight of one or two persons, so as to properly distribute the strain upon the springs of the bed-bottom, and also to provide the individual sections of the mattress-body with ventilators which carry off the heat, and thereby serve to not only maintain the mattress-body cool, but in a thoroughly sanitary and hygienic condition.

With these and other objects in view, which will more readily appear as the nature of the invention is better understood, the same consists in the novel construction, combination, and arrangement of parts hereinafter more fully described, illustrated, and claimed.

While the essential features of the invention may be susceptible to some modifications without departing from the scope thereof, still the preferred embodiment of the improvements is shown in the accompanying drawings, in which—

Figure 1 is a perspective view of a mattress 40 constructed in accordance with the present invention. Fig. 2 is a transverse cross-sectional view of the mattress in its spread-out condition. Fig. 3 is a similar view showing the mattress-body in its folded condition. 45 Fig. 4 is an enlarged detail in perspective of an end portion of one of the mattress-sections, showing the end covering-flaps unfolded and exposing the ventilating-head within the end of the section. Fig. 5 is an enlarged 50 detail sectional view through one end of one of the mattress-sections.

Like numerals of reference designate corresponding parts in the several figures of the drawings.

Referring to the accompanying drawings, 55 the numeral 1 designates the mattress-body, formed of a series of longitudinally-arranged parallel parallelepiped sections 2, flexibly connected together at their contiguous top edges to permit of the body being arranged in a flat 60 spread-out condition for use on the spring bed-bottom or transversely folded into a compact condition, as shown in Fig. 3 of the drawings. In constructing the said mattress-body, composed of the duplicate flexibly-connected 65 sections 2, the entire covering for the same consists of a single top sheet 3 and a body-sheet 4. The two cover-sheets 3 and 4 for the mattress are made of the usual cloth or textile material; but it will of course be understood that any equivalent material that could enter into the formation of the mattress 70 may be used in making the top and body sheets 3 and 4.

In carrying out the present invention the 75 single top sheet 3 for the mattress-body is cut in a rectangular form and is of a size corresponding to the size of the bed in connection with which the mattress is to be used, while the main body-sheet 4 of the mattress is cut 80 much larger than the top sheet and is formed with a plurality of parallel longitudinal folds 5. These parallel longitudinal folds of the body-sheet 4 extend lengthwise of the mattress-body at regularly-spaced intervals apart 85 and are stitched or otherwise suitably fastened, as at 6, to the under side of the top sheet 3, whereby a series of separate and independent closed filling-pockets constituting the individual sections 2 are formed, which 90 filling-pockets are designed to be packed with the usual or any suitable filling material 7, which when closely packed into the pockets fills the same out and imparts thereto the parallelepiped form, whereby the same are 95 of a cross-sectionally-rectangular shape. This shape of the individual sections 2 of the mattress-body is preferably maintained by stitching tucks 7^a along the bottom corners of the sections, as plainly shown in Fig. 2 of the 100 drawings.

From the foregoing description it will be

observed that each parallelepiped section 2 of the mattress-body receives a separate filling and is inclosed at three sides by the main body-sheet 4 and at the upper or top side by 5 the top sheet 3, which top sheet, therefore, necessarily forms the top covering for the pockets of all of the individual sections 2, and by reason of stitching or otherwise fastening the body-sheet at the point 6 to the 10 top sheet the latter necessarily forms a flexible hinge connection between the contiguous top edges of the adjacent sections, thereby permitting the body to be readily spread out or the sections folded one upon the other, as 15 shown, respectively, in Figs. 2 and 3 of the drawings.

Each section 2 of the mattress-body has extended from the sides thereof and at each end the end covering-flaps 8 and 9, respectively, 20 which are folded in and overlap upon the outer side of an end ventilating-head 10, fitted inside of the end of the section adjacent to the flaps. The end ventilating-head 10, which is fitted within each end of each body-section 25 2 of the mattress, preferably consists of a rectangular block of wood, although it will be understood that the same may be made of any other material suitable for the purpose, and by reason of the rectangular shape 30 thereof the said ventilating-heads 10 not only serve to permit of freely ventilating each section of the mattress-body from both ends thereof, but at the same time serve to stiffen and strengthen the body-sections and to maintain 35 the cross-sectionally-rectangular shape thereof.

The ventilating-head 10 within each end of each body-section 2 is provided with a screened 40 ventilating-opening 11, which provides communication between the interior of the mattress-body section and the outer air, and in order to provide for exposing the screened 45 ventilating-openings 11 of the heads 10 the end covering-flaps 8 and 9 at each end of the sections are arranged to have their edges terminate short of each other to leave an opening in communication with the screened 50 ventilating-openings 11. The ventilating-heads 10 are preferably retained in place by means 55 of tacks or other suitable fasteners passing through the coverings 3 and 4 and into the edges of the heads, and the end covering-flaps 8 and 9 may be likewise fastened directly to the outer sides of the said ventilating-heads, 60 as plainly shown in the drawings. It will thus be seen that the end flaps 8 and 9 at the ends of the mattress-body sections completely cover the ventilating-heads 10 with the exception of the screened ventilating-openings 11 thereof, 65 which are always left exposed for the thorough aeration of the mattress-body sections, as well as the ventilation thereof. The covering-flaps 9 are designated as the flaps extending from the sides of the body-sections 2, 70 and which are secured flat upon the outer sides of the ventilating-heads; but in carrying out the invention the other flaps 8, folded

in from the upper and lower sides of each body-section 2, are designed to be padded with suitable padding 12, filled into the pockets 70 between the outer faces of the heads 10 and the said flaps 8, thereby providing protective cushions at the ends of the mattress-body to prevent the ventilating-heads from being knocked out of place or the bed injured by 75 rough handling of the mattress.

By reason of the construction described it will be observed that the several individual sections 2 of the mattress-body are of comparatively-small dimension in cross-section, 80 thereby permitting of using short hair for filling the pockets. The mattress can therefore be constructed with much less expense than mattresses formed in the usual way and which necessitate the use of long hair to prevent 85 the formation of lumps. It will also be observed that the construction of the mattress-body with a plurality of individual sections permits the body to freely adjust itself to the weight of the person or persons thereon, especially in the case of two persons of different weights occupying the bed, in which event the mattress will tend to evenly distribute the strain upon the bed-bottom.

It is important in carrying out the invention 95 that the individual sections 2 extend lengthwise of the mattress-body to admit of more compact folding.

Other advantages will readily suggest themselves to those skilled in the art, and it will 100 be understood that changes in the form, proportion, and minor details of construction may be resorted to without departing from the principle or sacrificing any of the advantages of this invention.

Having thus described the invention, what is claimed as new, and desired to be secured by Letters Patent, is—

1. A mattress comprising a body formed of a series of longitudinal sections flexibly connected at their contiguous top edges, ventilating-heads at the ends of said sections, and pads partly inclosing the ventilating-heads, substantially as described.

2. A mattress comprising a body formed of a plurality of independent sections each provided with padded ends, and perforated ventilator-heads arranged in and partly inclosed by the padded ends for communication with the mattress-sections, substantially as set forth.

3. A mattress comprising a body formed of a plurality of independent sections each of which is provided with padded ends, and ventilator-heads within the padded ends of each section of the body, said ventilator-heads conforming to the cross-sectional shape of the sections and provided with ventilating-openings, substantially as set forth.

4. A mattress comprising a body formed of a plurality of independent parallel sections having covering-flaps extended from their ends, and ventilating-heads fitted within the opposite ends of each section of the body and

adapted to have said cover-flaps folded upon and secured to their outer sides, substantially as set forth.

5. A mattress comprising a body having a series of independent sections, each provided at the opposite ends thereof with a plurality of covering-flaps forming extensions of the covering for the sections, and ventilating-heads fitted within the opposite ends of each 10 section, and adapted to have the covering-flaps folded down and secured to their outer

sides, certain of said covering-flaps being padded to form end cushions for the body-sections, substantially as set forth.

In testimony that I claim the foregoing as 15 my own I have hereto affixed my signature in the presence of two witnesses.

JAMES W. CASE.
